UNITED STATES PATENT OFFICE.

JOHN H. TORNEY, OF WASHINGTON, DISTRICT OF COLUMBIA, ASSIGNOR OF ONE-THIRD
TO HARRY WILSON AND ONE-THIRD TO JOHN C. RINEHART, OF WASHINGTON,
DISTRICT OF COLUMBIA.

RIFLING-MACHINE.

1,067,285.

Specification of Letters Patent.

Patented July 15, 1913.

Application filed July 21, 1910. Serial No. 573,017.

To all whom it may concern:

Be it known that I, JOHN H. TORNEY, a citizen of the United States, residing at Washington, in the District of Columbia, have invented certain new and useful Improvements in Rifling-Machines; and I do hereby declare the following to be a full, clear, and exact description of the invention, such as will enable others skilled in the art to which it appertains to make and use the same.

This invention relates to rifling machines of the class used in forming the grooves in the rifling of ordnance.

15 The invention especially relates to what is known as the rifling head of such a machine.

In rifling wherein the grooves are of uniform depth and width throughout, the portion of the band which is forced into the grooves is worn away to some extent during the passage of the projectile through the bore of the gun. This causes a space to be left between the side of the groove 25 and the portion of the band projecting therein with the result that the gases produced by the combustion of the powder escape through the opening left at a very high velocity. The intense friction set up by these gases together with the high degree of temperature causes the metal of the band to wear away more rapidly and also causes scouring of the metal of the groove to the great injury of the gun. It has long 30 been recognized that this might be prevented by tapering the grooves so that they would have less cross sectional area at the muzzle than toward the breech but it has heretofore been impracticable to so taper 40 the grooves.

The principal object of the present invention is to provide a mechanism adapted to rifle a gun in such manner that tapering grooves will be formed therein, the taper 45 being in the depth or in the depth and width combined.

In the art of rifling guns a head is employed which fits the bore of the gun and carries tools which cut the grooves by a 50 planing operation. These tools have heretofore been lubricated by oil introduced against the movement of the rifling head, the latter cutting as it moves from muzzle to breech while the oil has been introduced

in a stream toward the muzzle. The effect 55 of this is to drive the small chips formed against the rifling head with the consequence that the tools become rapidly dulled by working over these chips.

A second object of the invention is to 60 provide a lubricating means wherein the lubricant will be forced through the head in the same direction as that in which the head is moving when cutting is being effected so that the chips formed will be 65 washed away from the head and injury to the edges of the rifling cutters due to the chips will be eliminated.

A third object of the invention is the provision of a mechanism wherein tapering 70 grooves may be cut in a portion of the length of the bore, the remaining portion of such bore being rifled with parallel sided grooves of uniform depth.

With the above and other objects in view, 75 as will be hereinafter apparent, the invention consists in general of a rifling head provided with mechanism arranged to cut grooves tapering in depth from muzzle to breech of a gun.

The invention further consists in certain novel details of construction and combinations of parts hereinafter fully described, illustrated in the accompanying drawings and specifically set forth in the claims.

In the accompanying drawings, like characters of reference indicate like parts in the several views, and:—Figure 1 is a side elevation of a portion of a rifling machine showing the improved mechanism in position 90 thereon; Fig. 2, an end elevation of a portion of such a machine provided with the improved mechanism; Fig. 3, a longitudinal median section through a rifling head constructed in accordance with this invention; Fig. 4, a face view of such a head; Fig. 5, a section on the line 5—5 of Fig. 3; Fig. 6, a detail view of a rifling head body constructed in accordance with this invention; Fig. 7, an end view of the body; Fig. 100 8, a section on the line 8—8 of Fig. 6; Fig. 9, a view of the rear of the face plate; Fig. 10, a section on the line 10—10 of Fig. 9; Fig. 11, a section on the line 11—11 of Fig. 9; Figs. 12 and 13, detail views of a certain sleeve used herewith; Figs. 14 and 15, detail views of a certain dial plate used herewith; Figs. 16 and 17, detail views of

a portion of a locking device used herewith; and, Figs. 18 and 19, details of an arm used herewith.

It is well understood in the art that a rifling machine consists of a bed having a suitable gun supports formed thereon, a fixed rifling bar support through which the bar slides and rotates, a movable carriage traveling over said bed and supporting and carrying the rifling bar, a rifling head on the bar and suitable actuating means for said bar. In the present instance only those parts of such a machine have been shown as either form a part of this invention or 15 directly coöperate therewith, and the bed is indicated at 10.

On the bed 10 is a carriage supporting a fixed rifling bar bearing through which the bar slides, the bearing being provided with 20 guide means to engage the groove common to rifling bars. This carriage and support are of the ordinary form.

At 13 is indicated the movable carriage whereto is attached the rifling bar bearing 25 14. This bearing or support 14 carries a rifling bar 15, the bar being so secured to the support that as the support travels the bar will also move. The bar 15 is provided with the usual rifling groove 16 and the support 30 has suitable guide means, details of which are not here shown as forming no specific form of the invention. This bar 15 is hollow throughout its length and is provided on the end adjacent the gun with external 35 screw threads 17.

The rifling head consists of a cylindrical body portion 18 on which is fitted a jacket 19, the jacket closely engaging the rifling head and being of a bore corresponding 10 properly with the diameter of the gun to be rifled. This jacket 19 is held from movement rearwardly on the body by means of a ring 20 which is screwed on to a reduced and threaded portion 21 formed on what is 15 preferably termed the rear or rifling bar end of the body 18. This body is provided with a second reduced portion 22 which is cylindrical in form and on this reduced portion is held the forward end of a sleeve 23, 20 the bore of the sleeve being reduced at said forward end to fit on the body portion 22 while the remainder of the sleeve is spaced from said body. Adjacent the reduced portion 22 is a third reduced portion 24 which 25 is threaded exteriorly and between the sleeve 23 and said threaded portion 24 is fitted a threaded ring 25 which serves to hold the sleeve 23 so that the latter is freely rotatable on the portion 22 while it is prevented 30 from movement longitudinally of said body. The body 18 terminates toward the rear in a tapered shank 26 having a key 27 fitted 35 therein and the rear portion of the sleeve 23 is threaded interiorly as at 28 and provided 40 exteriorly with a polygonal surface forming

a nut 29 for the reception of a wrench. The rifling bar 15 is hollow interiorly as previously noted and the rear end of this bar is formed with the hollow portion of uniform diameter throughout as indicated at 30 70 while the forward end of the bar is provided with a tapered bore 31, the taper being such as to fit the tapered shank 26 and the bore being provided with a key seat 32 for the reception of the key 27. The head is connected to the bar by inserting the shank 26 in the tapered bore 31 in such manner that the key 27 slips into the key seat 32, thus permitting the engagement of the threads 28 on the sleeve 23 with the thread 35 17 on the bar. The sleeve 23 is then rotated and the shank 26 forced firmly back into the tapered bore 31 until the two parts are rigidly connected. The forward end of this body 18 is provided with a series of radial slots 33 here shown as four in number although any other number which may be found preferable can be used. Between the adjacent slots 33 there are provided threaded bolt receiving recesses 34. On the front of this head is a face plate 35, the face plate being secured to the head by suitable bolts 36 which pass through the face plate and into the threaded recesses 34, the heads of these bolts being received in countersunk recesses 37 formed in the face plate 35. In the slots 33 are held cutter holders 38. Each of these cutter holders is provided with a pocket 39. Extending across the pocket 39 of each of these holders is a pivot pin 40 100 and the walls of the holder pocket 39 are provided with portions 41 concentric with the pivot pin 40. These concentric walls are located toward the outer end of the respective pocket and held in this outer end is the body 42 of a blade carrier which fits this outer end of the pocket 39 and is provided with arcuate surfaces fitting the surfaces 41. This body 42 is pivoted on the pin 40 so that it is freely rotatable thereon. Extending 105 into the inner end of the recess is a stem 43 which is formed on the body 42. Each of these cutter holders 38 is provided with an opening 44 extending through the rear wall and communicating with the pocket 39, the rear end of this opening being threaded for the reception of a screw plug 45. The front wall of each of said cutter holders is also provided with an opening indicated at 46, the opening being threaded and aligned with 110 the opening 44. Through this opening 46 extends a threaded pin 47 having a square head 48 formed on its forward end for the reception of a suitable wrench. Between the portion 43 and the plug 45 is a spiral 115 spring 48' which normally forces said portion 43 forward against the respective pin 47. By this means the blade carrier is permitted to move in one direction about its pivot by the compression of its spring 48' 120

125 130

while its movement in the opposite direction is prevented by its pin 47. Each of these blade carriers is provided with a pocket or seat 49 wherein is held a cutting blade 50, the blade being secured in position by a suitable screw 51.

The parts just described are so arranged that by the proper adjustment of the pins 47 the cutter blades 50 will bite into and cut 10 the metal of the gun bore as the head moves forward but when the head moves rearward to take position for the next succeeding cut the springs 48 will compress and relieve the pressure on the edges of the respective cutting tools. For the purpose of adjusting the pins 47 these pins project forward through 15 slots 52 formed in the face plate 35.

The body 18 of the head is provided with a centrally disposed longitudinal opening 20 53 which extends from one end to the other of said head and communicates with the bore or opening extending through the rifling bar. In the forward end of the opening 53 there is mounted a sleeve 54 the forward 25 end of which projects into the space formed by the intersection of the slots 33. This sleeve is provided at the forward end with tapered dove-tailed portions 55 which co-operate with dove-tailed portions 56 formed 30 on the members 38, the portions 56 being likewise tapered to conform to the taper of the portions 55. The taper of these portions is such that if the sleeve 54 be moved forwardly in the head 18 the members 38 35 will be moved radially outward in their respective slots while if the sleeve 54 be moved rearwardly said members will be drawn inward in these slots. For the purpose of moving the sleeve in this manner two arrangements are provided, one a manual adjustment and the other the automatic means 40 by which the sleeve is moved forward as the rifling head is carried forward by the rifling bar.

45 There will first be considered the means by which the cutters are caused to move outwardly from the axis of the rifling head during the movement of the bar from the muzzle to the breech of the gun and inwardly when the movement is reversed. As previously noted both the rifling head and the rifling bar are hollow throughout their 50 lengths. Through the rifling head extends a rod 57 having at one end a head 58 provided with a socket 59 polygonal in cross section. Through the rifling bar extends a rod 60 having a polygonal end 61 of such size as to fit the socket 59 when the parts are assembled. This rod 60 projects beyond the 55 rifling bar and is provided near its rear end with a collar 62 which contacts with the rear end of the rifling bar when the parts are in position, the bar being fitted with a suitable washer 63 to permit a close contact 60 to be made. Located on the carriage 13 is a

standard 64, the standard being preferably toward the rear of the carriage. The carriage is provided with a T-slot 65 and the standard 64 is secured to the carriage by means of T-bolts 66, the latter passing 70 through the base of the standard and being provided with nuts 67 by means of which the standard may be fixed in position on the carriage or, if the nuts be loosened, may be allowed to slide along said carriage. This 75 standard is provided with a head 68 having a lateral slot 69 formed therein, the slot preferably being in the same horizontal plane with the axis of the rifling bar. Upon the rear end of the rod 60 is secured an arm 80 70 provided with a split clamp 71 the parts of which are drawn together by a suitable bolt 72 after the clamp has been placed upon the rod 60. The end of this arm 70 opposite the clamp is provided with a head 73 adapted to fit in the slot 69. It will thus be observed that when the arm is properly clamped on the rod and the head 73 held in the slot 69 the rod will be prevented from rotation. Upon the forward end of 90 the rod 57 is a threaded sleeve 74 which is held within the sleeve 54, the latter being provided with suitable threads to engage the threads on said sleeve 74. This sleeve is normally kept in engagement or locked 95 to the rod 57 by means hereinafter to be described. Now, in the operation of this feature of the invention, as the rifling bar is moved forward it carries the rifling head with it and by reason of the guide in the front support the rifling bar is rotated to give the proper twist to the rifling. Meanwhile the rod 57 is held from rotation by its connection with the rod 60, the latter being held from rotation by the arm 70. Now, if 100 the sleeve 74 be locked to the rod 57 the sleeve 54 will rotate on the sleeve 74 with the result that the sleeve 54 will be advanced by the action of the threads on said sleeves in a direction toward the front of 110 the rifling head. By means of the beveled surfaces on the sleeve 54 and the members 38 the latter will move radially outward and will carry the cutter blades 50 with them thus causing said blades to cut a 115 deeper groove the farther the rifling head is advanced.

In order to prevent longitudinal movement of the sleeve 74 on the rod 57 the face plate 35 is provided with a centrally disposed threaded opening wherein is held a threaded plug 75. This plug 75 is also provided with a central opening wherethrough passes a cylindrical portion of the sleeve 74 and the forward end of the opening in said 120 plug is recessed for the reception of a collar 76 formed on said sleeve 74 and still further recessed to a greater diameter than the collar receiving recess for the reception of a plate 77 which is held by suitable screws 130

to the plug 75. This plate rests against the forward side of the collar 76 and the collar and its sleeve are thus prevented from longitudinal movement with respect to the head 5 18. The sleeve 74 is continued forwardly through the plate 77 and has fixed thereon a nut 79. This nut carries a dial plate 78 provided with suitable graduations and having the graduated portion brought to a 10 knife edge bearing against the plug 75, the latter being provided with an index adapted to indicate the starting point from which the measurements taken by said graduations are made. In front of the nut 79 is a second 15 plate 80 preferably formed integral with the nut. The rod 57 extends through this second plate 80 and on the end of this rod is fixed a dial plate 81 carrying a boss 82 wherethrough passes a spring pressed 20 plunger 83 provided with a knurled head 84. The plate 80 is provided with a series of recesses 85 arranged concentrically to the center of said plate and at the same distance from said center as the center of the 25 plunger 83, the latter being thus adapted to fit within any one of said recesses 85. Now so long as the plunger is engaged in one of the recesses the sleeve 74 and rod 57 will be locked together so that one cannot rotate 30 without the rotation of the other. When it is desired to move the sleeve 54 forward as when in setting the depth of the cut to be taken, the knurled head 84 is grasped and the plunger 83 withdrawn from the respective recess 85 in which it may be engaged. 35 A wrench is then applied to the nut 79 and the latter is rotated. This will cause the rotation of the sleeve 74 and actuate the sleeve 54 to move the cutters outward in 40 the manner previously described.

Considering now the manner in which the oiling is accomplished. The rod 60 has its rear end reduced as at 85 and provided with a suitable pipe threads for the reception of an 45 oil pipe leading from the usual oil pump common to rifling machines. Furthermore, the rear end of this rod 60 is recessed as at 86 to provide an oil passage and the forward end of this recess extends forwardly 50 of the collar 62 and is there provided with ports 87 which open into the space between said rod and the bore of the rifling bar. As previously noted this bore is continuous with the bore 53 in the rifling head. The rifling 55 head is provided intermediate its ends with a plurality of ports 88 which lead radially outwardly through the head to transverse oil grooves 89 formed circumferentially of the surface of said body and communicating 60 each with a series of forwardly extending longitudinal oil grooves 90 which terminate between the slots 33 in ports 91. By reason of the fact that the jacket 19 is a close fit on the body it covers the grooves both transverse and longitudinal and thereby makes

70 passages for the oil and directs the same to the ports 91. The ports 91 are arranged to communicate with the inlet ends of ports 92 formed through the face plate and so disposed that the streams of oil issuing from them flow directly in front of the cutters and with other ports 93 also formed in said face plate and lying in radial planes but forwardly and outwardly directed, the latter ports being for the purpose of lubricating the lands of the rifling during the passage of the head through the bore of the gun.

75 For the purpose of preventing the oil in the bore 53 of the head from passing into the forward end of said bore and coming in contact with the sleeve 74, thus injuring the threads through the minute chips carried therein cutting said threads, the bore 53 is provided with a suitable stopper or plug. 80 In the present instance there is used to form this stopper a collar 94 which is fixed upon the rod 57 and forward of this collar is a second collar 95 against which rests packing 96 held in position by a follower plate 97, 90 the latter being forced firmly against the packing by a spring 98 interposed between the collar 94 and said follower plate.

85 From the foregoing it will be plain that oil introduced through the rear end of the 95 rod 60 will flow forwardly between said rod and the wall of the bore 30 into the bore 53 of the head. Thence the oil will pass through the openings 88 into the grooves 89 from where it will flow forwardly through the 100 grooves 90, ports 91, and ports 92 and 93 in front of the cutters and the rifling head, the streams of oil being all directed away from the face of the rifling head so that they carry the chips cut away from said head and prevent injury to the cutters by said chips.

105 In order to arrange for cutting a portion of the groove of uniform depth throughout it is merely necessary to release the arm 70 from the slot 69 when the arm will rotate 110 with the rifling bar and the sleeve 54 thus remain stationary with relation to the rifling head. To this end a knock-off arm 99 is provided which is adjustable along the bed 115 of the rifling machine and the arm is arranged to project inwardly in the path of the standard 64. When it is desired to change this method of cutting the grooves the nuts 67 are loosened and the arm 99 placed in the desired position. Now as the 120 carriage advances through the first portion of the cut the rod 60 with the parts connected thereto will be held from rotation and the cutters will be moved gradually outward as the rifling bar progresses from the muzzle 125 toward the breech. When the standard 64 reaches the point at which it engages with the arm 99 the carriage 13 will continue to move forward but the standard 64 will be stopped. As the carriage 13 moves 130

forward it carries with it the arm 70 which thus becomes disengaged from the groove 69 and the arm is thus permitted to rotate as previously described with the effect of stopping the movement of the sleeve 54 toward the face plate. It will thus be seen that the device may be set for either cutting grooves which taper throughout the entire length or for cutting grooves which taper a portion of the length and are of uniform depth throughout the remainder, or, by removing the arm 70 may be used for cutting grooves of uniform depth throughout their entire length.

15 In the operation of the device the cutters are moved out by hand by releasing the plunger 83 and using a wrench on the nut 79 in the manner previously described until they have been set to cut the required depth 20 of groove. The machine is then started and the cutters will engage the metal of the gun and cut the same away to form the groove, the cutters moving farther out as the head advances provided it be desired to cut a

25 tapering groove and the machine be arranged therefor in the manner previously described. When the rifling head has reached the forward limit of its movement the rifling machine is reversed and the head drawn back through the bore. The springs 48' will relieve the pressure on the cutters and at the same time the sleeve 54 will be drawn back and pull the carriers 38 inward, thus preventing jamming of the cutters in the shallow portions of the groove. The rifling bar having reached the rearward limit of its stroke adjustment is again made for a second depth of cut and the operation repeated, these cuts and adjustments being alternately 40 made until the grooves are completed.

It is to be understood that the pitch of the screw and graduations of the dial plate may be readily arranged so that each graduation indicates a definite fraction of an 45 inch or other measurement, thus greatly assisting in the setting of the cutters and it is also to be observed that the number of recesses 85 and their spacings may also be arranged to assist this setting.

50 It will be obvious that the cutters may be drawn inward at any time, even if the head be in the bore of a gun, by releasing the arm from the standard and rotating the rod 60 in the proper direction by using the 55 arm as a lever for this purpose. It will also be obvious that any change in the taper of the dove-tails 55 and 56 or in the pitch of the screw connecting the members 54 and 74 will alter the rate of outward feed of the 60 cutters so that by properly proportioning these parts any desired changes of feed may be obtained.

There has thus been provided a simple and efficient device of the kind described 65 and for the purpose specified.

It is obvious that minor changes may be made in the form and construction of this invention without departing from the material principles thereof. It is not therefore desired to confine the invention to the exact 70 form herein shown and described, but it is wished to include all such as properly come within the scope of the appended claims.

Having thus described the invention, what is claimed as new, is:

1. In a rifling machine, a rotatable rifling head provided with laterally opening slots, a cutter carrier movably mounted in each of said slots, said cutter carriers each having its inner face at an angle to the axis of said head, a sleeve having inclined outer faces engaging the inner faces of said carriers, said sleeve being provided with a threaded bore, a threaded member engaged in the threaded bore, means to prevent the rotation of said member, and a release mechanism for said means operable upon completion of a predetermined movement of said head.

2. In a rifling machine, a rotatable rifling head provided with laterally opening slots, a cutter carrier movably mounted in each of said slots, said cutter carriers each having its inner face at an angle to the axis of said head, a sleeve having inclined outer faces engaging the inclined faces of said carriers, said sleeve being provided with a threaded bore, a second sleeve threaded to fit said bore, a rod running through said second sleeve, a releasable locking device connecting said second sleeve and rod, and means to prevent the rotation of said rod.

3. In a rifling machine, a rotatable rifling head provided with laterally opening slots, a cutter carrier movably mounted in each of said slots, said cutter carriers each having its inner face at an angle to the axis of said head, a sleeve having inclined outer faces engaging the inclined faces of said carriers, said sleeve being provided with a threaded bore, a second sleeve threaded to fit said bore, a rod running through said second sleeve, a releasable locking device connecting said second sleeve and rod, means to prevent the rotation of said rod, and a release mechanism for said means operable upon completion of a predetermined movement of said head.

4. In a rifling machine, a rifling bar, a carriage supporting one end of said rifling bar, a rifling head on the opposite end of said bar, cutters carried by said head and movable toward and from the axis of said bar, an operating mechanism connected to said cutters to move the cutters relative to 120 said axis and including an actuating element, said operating mechanism being actuated by the relative rotation of the head and actuating element, a rod extending through said rifling bar, releasable locking 125

- means to immovably connect said rod and actuating element, and coacting engaging means on said rod and carriage to prevent the rotation of said rod.
5. In a rifling machine, a rifling bar, a carriage supporting one end of said rifling bar, a rifling head on the opposite end of said bar, cutters carried by said head and movable toward and from the axis of said bar, an operating mechanism connected to said cutters to move the cutters relative to said axis and including an actuating element, said operating mechanism being actuated by the relative rotation of the head and actuating element, a rod extending through said rifling bar, releasable locking means to immovably connect said rod and actuating element, coacting engaging means on said rod and carriage to prevent the rotation of said rod, and a release mechanism for said coacting engaging means operable on completion of a predetermined movement of said bar.
6. In a rifling machine, a rifling bar, a carriage supporting one end of said rifling bar, a rifling head on the opposite end of said bar, cutters carried by said head and movable toward and from the axis of said bar, an operating mechanism connected to said cutters to move the cutters relative to said axis and including an actuating element, said operating mechanism being actuated by the relative rotation of the head and actuating element, a rod extending through said rifling bar, releasable locking means to immovably connect said rod and actuating element, an arm fixed on said rod, and a standard on said carriage provided with a slot to receive the end of said arm and hold the same from movement.
7. In a rifling machine, a rifling bar, a carriage supporting one end of said rifling bar, a rifling head on the opposite end of said bar, cutters carried by said head and movable toward and from the axis of said bar, an operating mechanism connected to said cutters to move the cutters relative to said axis and including an actuating element, said operating mechanism being actuated by the relative rotation of the head and actuating element, a rod extending through said rifling bar, releasable locking means to immovably connect said rod and actuating element, an arm fixed on said rod,
- a standard movable on said carriage and provided with a slot to receive the end of said arm and hold the same from movement, and a stop member fixed in the path of said standard to move the standard out of engagement with the arm.
8. In a rifling machine, a rifling head, and cutters carried by said head, said head being provided with a chamber formed therein and further having lubricant ducts leading from said chamber and provided with mouths arranged to direct the lubricant in advance of and in the paths of said cutters, said head also having other ducts leading from said chamber and provided with mouths arranged to direct the lubricant outwardly in advance of said head and between the paths of said cutters.
9. In a rifling machine, a rifling head, and cutters carried by said head, said head being provided with a chamber formed therein and further having lubricant ducts leading from said chamber and provided with mouths arranged to direct the lubricant in advance of and in the paths of said cutters, said head also having other ducts leading from said chamber and provided with mouths arranged to direct the lubricant outwardly in advance of said head and between the paths of said cutters; in combination with a rifling bar having a bore extending therethrough and communicating with said chamber, and an oil pipe connection carried by said bar.
10. In a rifling head, a body having a chamber formed therein and provided with lateral openings leading from said chamber to the outside of the body and located in spaced relation to the front end of the body, said body being further provided with peripheral grooves in which said openings terminate and with longitudinal grooves extending forwardly from said peripheral grooves, a jacket surrounding said casing and covering said grooves, and a face plate on the front of said body and having ports extending through the plate and communicating with said grooves.

In testimony whereof, I affix my signature, in the presence of two witnesses.

JOHN H. TORNEY.
